CLOSURE CONTROL

Carl A. Olson, East Rockford Station, Ill.

Application September 10, 1946, Serial No. 695,851

5 Claims. (Cl. 215—64)

1

This invention relates to a closure-control element for catsup bottles.

It is an object of the present invention to provide a closure-control element with means utilizing the formation of the bottle top for maintaining the closure element guided upon the top and retained thereon against vertical displacement when in its closed position.

It is another object of the invention to provide an operating lever arrangement for the closure element which can be adjusted vertically along its support to adapt the cap and the attachment to different shaped bottles.

According to the invention, there is a main support adapted to be clamped about the bottle. A slideable cap is adapted to be slid over the top opening of the bottle. This cap has depending members adapted to be guided by the annular recesses formed in the top of the bottle. The lever connected to the cap is mounted on a carrier which is in turn adjustable on the main support clamped to the bottle so that the cap can be adapted and made to fit properly different bottles with which the attachment is used.

For a better understanding of the invention, reference may be had to the following detailed description taken in connection with the accompanying drawings, in which:

Figure 1 is a side elevational view of the attachment in place upon the bottle and illustrating with dotted lines the movement of the cap over the bottle top opening and of the operating lever.

Figure 2 is an elevational view looking upon the face of the operating lever.

Figure 3 is a top plan view of the attachment and the bottle.

Figure 4 is a fragmentary view of a vertical portion of the support adapted to be clamped to the bottle.

Figure 5 is a cross-sectional view showing the connection of the lever carrier with the support and as viewed along the line 5—5 of Figure 2, and looking in the direction of the arrows thereof.

Figure 6 is a longitudinal cross-sectional view taken through the support, the lever and its carrier which is attached to the support, and as viewed along the line 6—6 of Figure 5 and looking in the direction of the arrows thereof.

Referring now to the figures, a bottle 10 is adapted to contain an attachment 11 embodying the features of the present invention. The bottle 10 has the usual annular recess 12 below the usual annular cap bead 13 which surrounds the bottle opening. The main support 14 is adapt-

2

ed to be clamped to the bottle below such recess and bead. Such support has vertically-spaced pairs of oppositely-extending bowed arms 15 and 16. The arms 15 and 16 are of different lengths and extend from a vertically-extending portion 17 having parallel slots 18 formed therein on opposite sides of a longitudinally and vertically-extending series of small recesses 19 which are formed in the outer surface of such portion, Figure 4. Spaced projections 21 and 22 of a lever carrier 23 extend into the slots 18. Such projections are bent inwardly to maintain the carrier upon the portion 17. A lever 24 is pivotally connected to the carrier by a pin 25. A spring 26 normally keeps the lever 24 pivoted inwardly. The lever 24 has a handle portion 27 adapted to be pressed inwardly by the thumb to a position shown in dotted lines Figure 1. The carrier 23 has a projection 29 on its upper edge 10 in alignment with the recesses 19 and is adapted to be seated in a selected one of such recesses to retain the carrier in a selected adjusted position on the portion 17.

The upper end of the upper lever arm 28 carries a cap 31 adapted to be extended over the cap head 13 of the bottle 10. This cap may have a gasket 32 so as to cause the cap to make an air-tight connection with the bottle. In order to insure that this air-tight connection be maintained, 25 there is depended downwardly from the sides of the cap strips 33 having horizontally extending portions 34 adapted to be guided in opposite portions of the annular recess 12 below the cap bead 13. These guided portions will positively 30 retain the cap upon the top and against vertical displacement therefrom.

In order that the cap will not be extended beyond its properly centered position, there is provided a depending lug 39 serving as a stop and 35 adapted to abut the cap head 13 when the cap is properly positioned thereon.

While various changes may be made in the detailed construction, it shall be understood that such changes shall be within the spirit and scope 40 of the present invention as defined by the appended claims.

I claim:

1. In a closure attachment for a bottle including a main support adapted to be clamped 50 to the bottle with a portion of said support extending longitudinally of said bottle, a lever carrier supported upon said portion for longitudinal adjustment thereon, means for maintaining the carrier upon said portion in its adjusted position, a lever on the carrier extending longitudi-

nally upwardly thereof, and a cap carried on the end of the lever adapted as the lever is operated to slide to and fro over the top of the bottle; the improvement comprising at least one guide slot formed in said portion and extending longitudinally thereof, said carrier having portions extending into said slot and mounting said carrier on said portion for longitudinal sliding movement, a longitudinally-disposed series of recesses formed in said portion adjacent to and parallel to said slot, a projection on said carrier, said projection being adapted to be seated in a selected one of said recesses whereby to lock said carrier in a selected longitudinally-adjusted position relative to said support.

2. In a closure attachment for a bottle including a main support adapted to be clamped to the bottle with a portion of said support extending longitudinally of said bottle, a lever carrier adjustably supported on said portion for longitudinal adjustment thereon, means for maintaining the carrier upon said portion in its adjusted position, a lever on the carrier extending longitudinally upwardly thereof, and a cap carried on the end of the lever and adapted as the lever is operated to slide to and fro over the top of the bottle; the improvement comprising a longitudinally-disposed series of recesses formed on said portion, a projection on said carrier, said projection being adapted to be seated in a selected one of said recesses whereby to lock said carrier in a selected longitudinally-adjusted position relative to said support.

3. In a closure for a bottle or the like, including a support having means for detachably connecting the same to said bottle with a portion thereof extending longitudinally of the bottle, a cap for the bottle, means for moving said cap to and from open and shut positions relative to said bottle, and carrier means adjustably mounting said last-named means on said support; the improvement comprising at least one guide slot formed in said portion and extending longitudinally thereof, said carrier means having portions extending into said slot and slidably mounting said carrier means on said portion for longitudinal sliding movement, a longitudinally-disposed series of recesses formed in said portion adjacent to and parallel to said slot, a projection on said carrier, said projection being adapted to be seated in a selected one of said recesses whereby to lock said carrier in a selected longitudinally-adjusted position relative to said support.

4. In a closure for a bottle or the like, including a support having means for detachably connecting the same to said bottle with a portion thereof

extending longitudinally of the bottle, a cap for the bottle, means for moving said cap to and from open and shut positions relative to said bottle, and carrier means adjustably mounting said last-named means on said support; the improvement comprising a longitudinally-disposed series of recesses formed in said portion, a projection on said carrier, said projection being adapted to be seated in a selected one of said recesses whereby to lock said carrier in a selected longitudinally-adjusted position relative to said support.

5. In a closure for a bottle or the like, including a support having means for detachably connecting the same to said bottle with a portion thereof extending longitudinally of the bottle, a cap for the bottle, means for moving said cap to and from open and shut positions relative to said bottle, and carrier means adjustably mounting said last-named means on said support; the improvement comprising a pair of laterally-spaced guide slots formed in said portion and extending longitudinally thereof, said carrier means comprising a pair of laterally-spaced inwardly-directed projections extending into said slots, means for retaining said projections in said slots to slidably mount said carrier means on said portion, means mounting said second-named means on said carrier means for longitudinal sliding movement relative thereto, a longitudinally-disposed series of recesses formed in said portion intermediate said slots and parallel thereto, a projection on said carrier, said projection being adapted to be seated in a selected one of said recesses whereby to lock said carrier in a selected longitudinally-adjusted position relative to said support.
